FISH CLEANING TOOL

Leo R. Murnan, 4404 Woolworth St.,
Omaha, Nebr. 68105

Filed Mar. 24, 1972, Ser. No. 238,019

Term of patent 14 years

Int. Cl. D7—04

U.S. Cl. D7—106

FIG. 1

FIG. 2

FIG. 3

FIG. 4

FIG. 5

FIG. 1 is a side elevational view of a fish cleaning tool showing my new design, wherein the opposite side is a mirror image thereof;

FIG. 2 is a top plan view thereof;

FIG. 3 is a bottom plan view thereof;

FIG. 4 is a front elevational view thereof; and

FIG. 5 is a rear elevational view thereof.

I claim:

The ornamental design for a fish cleaning tool, substantially as shown and described.
